UNITED STATES PATENT OFFICE.

JAROSLAW K. KOSTKO, OF ST. LOUIS, MISSOURI.

METHOD AND MEANS FOR IMPROVING THE COMMUTATION OF DYNAMO-ELECTRIC MACHINES.

1,393,141.

Specification of Letters Patent.

Patented Oct. 11, 1921.

Application filed September 18, 1916. Serial No. 120,689.

To all whom it may concern:

Be it known that I, JAROSLAW K. KOSTKO, a citizen of the United States, residing at St. Louis, in the State of Missouri, have invented a certain new and useful Improvement in Method and Means for Improving the Commutation of Dynomo-Electric Machines, of which the following is a specification.

10 This invention relates to method and means for improving the commutation of dynamo-electric machines provided with commutators.

It is well known that in every commutating machine the reversal of current in a coil undergoing commutation is opposed by electromotive forces due to self-induction of the coil, to mutual induction of coils short-circuited by the brush, and to the magnetic

20 field set up by armature coils other than those which are undergoing commutation. Therefore, in order to extend the limit of sparkless commutation it is necessary to produce in the circuit of the short-circuited 25 coil an electromotive force opposite in direction to the above mentioned injurious electromotive forces. Moreover, if this electromotive force, which I shall call "reversing," is not only opposite in direction,

30 but at every moment, equal to the sum of injurious electromotive forces, then (considering as negligible the ohmic resistances of an armature coil and of leads connecting it to the commutator) perfect commutation will

35 result, the so-called "straight line" commutation, because in the usual system of graphic representation with time as abscissa and current as ordinate, the current in the short-circuited coil will be represented by a 40 straight line. It is well known that in this case the current density all along the brush contact surface is constant, and that the energy loss due to the contact resistance between the brush and the commutator is min-

45 imum depending only on physical properties of the brush. However, a "straight line" curve of the commutating current is by no means indispensable for perfect commutation. Commutation can be considered 50 as perfect if following conditions are satisfied: 1st, there is no sparking at the edges

of the brush; 2nd, at no point under the brushes the current density is so high as to be injurious to materials in contact; 3rd, the total energy loss, *i. e.*, the sum of losses 55 under the brush and in the device assisting the commutation, is very small. I have found that these conditions can be satisfied, and even a close approximation of straight line curve of commuted current can be obtained by intermittent application of a reversing electromotive force, which can be an alternating electromotive force, acting on the short-circuited coil while its direction 60 is such as to assist the commutation, and 65 made useful in a different way, but for the same object, during that part of its period when a direct application would be injurious for commutation because of the wrong direction. 70

Some of the objects of this invention, therefore, are to provide method and means to improve the commutation of dynamo-electric machines, by introducing at suitable periods into the armature coils undergoing 75 commutation an alternating electromotive force, which is applied in such a manner as to assist commutation and prevent sparking.

Further objects will appear from the detail description taken in connection with the 80 accompanying drawings, in which:

Figure 1 is a longitudinal section of a commutator;

Fig. 2 is an end view;

Fig. 3 shows a form of generator supplying the electromotive force assisting the commutation, in connection with a developed view of the commutator described with reference to Figs. 1 and 2, while Fig. 3a shows the application of this invention to 90 a machine;

Fig. 4 shows the curve of the electromotive force generated in this apparatus, together with the curve of magnetic flux required for this purpose; 95

Figs. 5, 6, 7 and 8 show different positions of brushes with relation to commutator described in Figs. 1 and 2, which occur when commutator and brushes are moving relatively to each other; 100

Fig. 9 shows a general shape of the curve of the current collected from a commutator

segment with particular reference to the relative brush and commutator positions shown in Figs. 5 to 8;

Figs. 10 to 14 illustrate the use of this invention in connection with commutators of usual construction, Fig. 10 showing curves of the reversing electromotive force required in such cases, and of the flux producing this electromotive force, and Figs. 11, 12, 13 and 14, showing different positions of brushes with relation to a commutator of usual construction;

Fig. 15 shows a general curve of the current collected from a commutator segment with reference to brush and commutator positions shown in Figs. 11 to 14;

Fig. 16 shows an improvement of the arrangement described in connection with Figs. 4 to 9;

Figs. 17 and 18 show the method of applying a reversing electromotive force at any stage of the commutation process other than the beginning and the end;

Fig. 19 shows the curve of the current in a short circuited coil when arrangement of Figs. 17 and 18 is used; and

Figs. 20 to 24 illustrate various methods of generating the reversing electromotive force without a source external to the machine.

This invention can be successfully applied to any kind of commutator, as will be explained below, but the best results will be obtained by the use of a specially constructed commutator, shown in Figs. 1 and 2.

All axial commutators (*i. e.* where the brush area extends in direction generally parallel to the shaft of the machine), whether of V ring construction, or shrink ring type, or any other construction, are, during process of manufacture, compressed in a strong metal ring, in order to form one solid body from the segments and insulating laminæ interposed between segments. Fig. 1 represents the longitudinal section and Fig. 2 the end view of a commutator in this stage of manufacture. In these figures, *a* is the metal ring, 1, 2, etc., are segments of copper or any conducting material, *s* are insulating laminæ. In order to adapt the commutator to the use in connection with this invention, a circular groove *d* slightly inclined on the axis of commutator, as shown, is cut out in the end opposite to the end which will be connected to the armature; next, a series of slots *e* in number equal to the number of commutator segments is milled in the same end of the commutator, their depth, width and position with reference to the insulation between segments being determined by the electrical features of the design, as will be explained below. The commutator then passes through the regular process of manufacture, as determined by its particular type, until it is

assembled and firmly secured on its spider. Groove *d* and slots *e* are then filled with a suitable plastic insulating compound, to which some hard ingredient can be added, to give it desired abrasive properties; then the compound is submitted to such hardening process as its nature may require; finally, the working face of the commutator is finished smooth. The developed face of the commutator appears then as shown in Fig. 3. It can be seen that by this process of construction the insulating compound is firmly anchored in the commutator.

The insulating compound filling slots *e* of the Figs. 1 and 2 forms what may be called "dead segments" 1^a, 2^a, etc. in Fig. 3. The commutator is shown in this figure as connected to a Gramme-ring armature, but it will be clear from description of invention that it is equally well applicable to drum or any other kind of armature, and to lap, wave or any other kind of armature winding. *C* is the main current collecting brush, preferably made of material having a comparatively low resistance of contact with the material of which the commutator segments are made. This brush can extend axially over the whole working face of the commutator and cover as many segments as required by the general features of the design, as this invention does not prescribe any definite relation between the peripheral width of the main brush and the width of a segment. *D* is an auxiliary brush preferably made of a material having comparatively high resistance of contact with the commutator segments. In the axial and peripheral directions, the dimensions of the brush *D* should not exceed the corresponding dimensions of a dead segment; it is clear, therefore, that the auxiliary brush *D* never short-circuits directly any of the armature coils. Arrow *f* shows the direction of motion of the commutator relatively to the brushes; it can be seen, therefore, that the process of commutation of a coil is always completed by the auxiliary brush *D*.

A disk or rotor *g* made from a magnetic material, preferably built up from thin iron laminations to the width required for the purpose, as hereinafter described, is keyed on the shaft of the machine in any convenient place. The rotor has projections *h* in the form of teeth and in number equal to the number of the commutator segments. A stator *j* of magnetic material, preferably built up from thin iron laminations and consisting of the yoke *k'* and projections *k*, *k*, is shaped and disposed with respect to the rotor, so as to produce the maximum variation of permeability in the magnetic circuit consisting of the stator yoke, projections *k* and the rotor when the latter is rotating with the shaft of the machine. Wound on the yoke of the stator is a coil *m* in which

the armature current or a definite portion of it is made to flow. A coil n is in inductive relation with coil m and is connected between the main brush C and the auxiliary brush D. A resistance r may be connected in series with the coil n . The line lead q is connected to the main brush. When the rotor g is rotating, an alternating electromotive force is generated in the coil n ; this electromotive force will be proportional to the exciting current flowing in m if the magnetic circuit is so proportioned that it will not become saturated with the highest possible values of current in m .

It is well known that sparking can occur both along the edge of the brush where commutator segments enter under it and along the edge where segments leave it. Along the leading edge of the segment an excessive current and energy density can be produced either by application of a too strong reversing electromotive force, when the current decreases at a too rapid rate, or by short-circuiting the coil in a strong field of adverse polarity, when the current at the beginning of commutation increases above its normal value; this usually occurs when the brushes are moved too close to the pole tips. With brushes set on neutral, and in absence of any artificial means of commutation sparking never occurs along the leading edge of the segment, especially if the armature coils possess high self induction, as in case of high voltage machines, to which this invention is especially applicable. Therefore, in most cases it is sufficient to introduce the reversing electromotive force toward the end of the commutation period only, leaving the commutation process to follow its natural course at the beginning. Figs. 4 to 9 illustrate the application of this invention to such a case.

In Fig. 4 let F represent the total magnetic flux linked with the coil n (Fig. 3) as function of time; E is the curve of derivatives of the curve F and can, therefore, be taken as representing the electromotive force induced in the coil n and acting between the main brush C and the auxiliary brush D. As the number of teeth of the rotor g is equal to the number of commutator segments, the period of the alternating electromotive force generated in the coil n is equal to the time during which the commutator rotates through an angle corresponding to one segment. Considering now more particularly the moment when the auxiliary brush has just left the segment 1 (Fig. 5), the above mentioned period of the electromotive force E , immediately following this moment, can be decomposed into three parts as follows: First, auxiliary brush is on the dead segment 2^a , main brush covers part of segment 2; beginning and end of this part of the period are represented respectively

in Figs. 5 and 6, (where, as well as in Figs. 7 and 8, the coil n and the rest of generating apparatus shown in Fig. 3 is omitted for simplicity's sake). Second, auxiliary brush and main brush both cover part of the segment 2; beginning and end of this part of the period are represented in Figs. 6 and 7. Third, auxiliary brush covers part of segment 2; main brush has left this segment and covers part of segment 3; beginning and end of this part of the period are shown in Figs. 7 and 8.

Assume now that the rotor g has been adjusted on the shaft so that the three parts of the period described above are made to correspond respectively to parts u , v and w of the electromotive force curve E Fig. 4. The action of the whole combination on the commutation of an armature coil o connecting segments 2 and 3 will then be as follows: From the moment when the coil o is short-circuited by the main brush to the moment when the auxiliary brush has just left segment 1 (Fig. 5), the process of commutation is not interfered with. During the part of the period represented by u , auxiliary brush is on the dead segment 2^a ; circuit of the coil n is open, and the current in the coil o still follows its natural course. During the part of period corresponding to v , auxiliary brush and part of the main brush bear upon the same segment 2. Should the connection between the two brushes contain nothing but a resistance, then, with the main brush of low contact resistance, only a small part of the current collected from the segment 2 would flow by the way of the auxiliary brush D; the bulk of the current would still flow through the main brush, and high final density and sparking under this brush might result. To prevent this the electromotive force generated in the coil n and corresponding to the period v is introduced between the main and the auxiliary brushes and so directed as to tend to produce in the connection between the brushes a current of the same direction as that which is collected by the auxiliary brush from the segment 2. Considering the current produced by electromotive force E as independent from, and superposed upon, the currents existing in the short-circuited armature coils, it can be seen that the total current due to E flows through the auxiliary brush, resistance r , and coil n , but in the main brush it divides itself in several branches, one of which closes through the contact resistance of the main brush and the metal of the segment 2, while all others close through the contact resistances of the main brush with commutator segments, resistances of leads between the commutator and armature coils, and resistances and reactances of the short-circuited coils. As the impedance of the latter circuits is much greater than the resistance

of the path through the segment 2, practically the whole current will flow through this segment. It is true that toward the end of this part of the period the contact resistance of the main brush with the segment 2 increases rapidly, but the electromotive force E is very small then, and lasts only a very short time, so that no appreciable amount of current will pass in the path of 5 the short-circuited coils. The action of the electromotive force E is, therefore, such that the resultant density of current between main brush and segment 2 will be equal to the difference of densities due to the current 10 collected from the armature and the current circulating in the local path through segment 2, while in the auxiliary brush the resultant density will be equal to the sum of the above densities; in other words, the effect 15 of the electromotive force E is to transfer the current collected from segment 2 from the main brush to the auxiliary brush. The action can be further improved by insertion of a small self induction 1. (Fig. 3) 20 in the circuit of the coil n , as will be explained below. During the part of the period w the segment 2 is in contact with the auxiliary brush only. Electromotive force E is now reversed in direction and assists 25 the reversal of the current in the short-circuited coil n ; it can be so adjusted as to produce zero density at the moment when the segment 2 leaves the auxiliary brush. A perfectly sparkless commutation is thereby 30 obtained.

The action of my device is illustrated in Fig. 9 showing the current ik collected from segment 2 during period $u v w$ in function of time. Curve I—P—M shows the current 40 ik for the commutation without auxiliary brush. Under ordinary circumstances sparking would occur in M where the density is represented as infinitely great, tangent to the curve ik being perpendicular to the axis 45 of time. Curve I—K—L—M' shows the current ik in the case when an auxiliary brush is used, but without any electromotive force between this brush and the main brush. Curve I—K—L—M' represents the case 50 when an electromotive force E is used and adjusted to give zero density at the moment when the auxiliary brush leaves the segment 2; the curve ik is then tangent to the axis of time in M.

55 If the specific contact resistance of the main brush is much lower than that of the auxiliary brush, then the current density between the main brush and segment 2, due to the armature current, rapidly increases 60 toward the end of the period v . In order to compensate it by means of a current set up in the opposite direction by the coil n it would be necessary to generate an electromotive force E rising to a considerable value 65 in an exceedingly short time. Now it is

difficult to do this by means of a generator such as described in Fig. 3; it is, therefore, preferable to insert a certain amount of self-induction (shown as coil 1 in Fig. 3) in the circuit of the coil n ; then at the end 70 of the period v the high density due to the current from the armature will be counterbalanced by the discharge current due to the energy stored in self induction 1. This latter, of course, can be incorporated in the 75 coil n or the resistance r . As explained above, the impedance of the armature will prevent this discharge current from flowing through the short-circuited coils rather than 80 through the segment 2.

It is well known that by virtue of the law of induction the area of the curve of E (Fig. 4) above the axis of time must be equal to the area below this axis; on the other hand, the reversing electromotive force during 85 time w must be considerably greater than E during the time v . One way to obtain suitable values for both is to extend the intervals u and v and shorten the interval w , but this can be done only at the expense 90 of some desirable features of electrical design. Another way of solving the difficulty is to design the generator of the reversing electromotive force with very poor regulation; it will be noted that it acts as generator, 95 delivering a current, only during interval v ; during w it acts as a motor, receiving the current. During v , as soon as the brush contact surfaces become sufficient, a fairly large current can be allowed to flow 100 between the main brush and auxiliary brush inside of the segment 2; if the regulation of the apparatus is poor, then, to equal upper and lower areas of the curve E will correspond very unequal areas of the curve E' 105 representing the terminal voltage of the apparatus, i. e., the voltage directly applied to the brushes. If a resistance r is connected in series with the generator, the ohmic drop 110 will still further diminish E' during w , thus increasing the effect of the poor regulation of the generator. As the amount of energy involved in the commutation process is very small, the loss in r will be entirely negligible, the more so because it occurs outside of the commutator and does 115 not affect the heating of the machine.

It is clear that in the most general case there must be as many stators j spaced around the disk g (Fig. 3), as there are 120 brush sets in the machine; but, if the winding is so designed that armature coils are always in the same phase of the commutation process under several sets of brushes, then the number of stators j can be reduced, 125 each stator carrying several independent coils n . However, in many cases it will be found of advantage to have a special stator j for each brush set, and excite the corresponding coil m by the current, or the frac- 130

tion of the current, of this brush set only, instead of the full armature current. The electromotive force E will then be always proportional to the current which it is supposed to reverse, regardless of unequal distribution of current between different brush sets; the number of equalizing connections can then be reduced, or they can even be dispensed with entirely.

10 It is well known that, in order to obtain maximum output from a given size of armature, as well as for economical production, low number of slots should be used, with several coil sides in each slot. However, this is objectionable for two reasons which affect the commutation adversely; first, the reluctance of the main magnetic circuit of the machine is variable, according to the relative position of the armature and field poles; the main flux of the machine is then variable, and induces in the short-circuited coils electromotive forces similar to those induced by the so-called "transformer" action in the short-circuited coils 20 of alternating current commutator motors. Sparking which results from circulating currents set up by these electromotive forces cannot be prevented by commonly used commutating devices, such as commutating poles; second: with several coil sides concentrated in the same slot the elements determining the value of the reversing electromotive force, such as self induction, mutual induction, etc., are different for different positions of the coil in the slot; therefore, in most cases, the best that can be done is to adjust the reversing electromotive force to an average or a maximum value; it frequently happens then that commutator segments are blackened at regular intervals. In accordance with this invention, however, to each armature coil corresponds a special projection h (Fig. 3); it is, therefore, possible to adjust the reversing electromotive force to suit the requirements of each individual coil by proper selection of the length and shape of the air gaps in the generating apparatus of Fig. 3, or by any other method of controlling the rate of 30 change of flux linked with coils n . The limit of sparkless commutation will then be considerably extended.

It has been assumed above that the disk g was rotating at the same speed as the commutator; the number of projections h (Fig. 3) was then made equal to the number of commutator segments. In case of slow speed machines the shaft of the disk g can be geared to the shaft of the commutator; the 40 number of projections h will then bear to the number of commutator segments the same ratio as the speed of the commutator shaft to that of the disk shaft. It is clear that the advantage resulting from assigning a specially shaped tooth to each indi-

vidual armature coil can be retained by suitable selection of ratio of speeds of the commutator and the disk.

Such as described above, the application of this invention involves the use of a specially constructed commutator. It is possible to retain most of its advantages in connection with commutators of usual construction, such as the one shown in development in Figs. 11 to 14, *i. e.*, in which segments 70 are separated from each other by thin insulating laminae s^1 of uniform thickness. This can be accomplished in the following way: current collecting apparatus consists, as before, of a main brush C^1 (Figs. 11 to 14) 75 and an auxiliary brush D^1 connected by a coil n^1 in which an alternating electromotive force E , is generated by variation of flux F^1 (Fig. 10) in a suitable generator, such as shown in Fig. 3. A resistance r^1 80 inductive or not, can be connected in series with n^1 if desired; external current is taken from the brush by means of a lead g^1 . Selection of brush properties and relative position of brushes are preferably determined 85 by following considerations: main brush may cover any desired number of segments and consist of material of medium contact resistance; auxiliary brush should be made as narrow as mechanical construction and required current capacity allow, and should be made of material of high contact resistance. Main and auxiliary brushes may extend over the whole working face of the 90 commutator and must be set at such distance 95 from each other that at the moment when the segment 2^a is leaving the main brush, the auxiliary brush has already completed the commutation of the coil o^2 and bears 100 entirely on segment 2^a . Then the time during 105 which the short-circuited coil o^1 is subject to the action of the commutating device can be divided in three parts: first; designated by v^1 in Fig. 10, during which 110 the auxiliary brush bears wholly on the segment 2^a , a portion of the main brush also covering this segment; Figs. 11 and 12 show relative positions of the commutator and brushes at the beginning and end of this period; second; interval w^1 during which 115 only auxiliary brush is in contact with the segment 2^a and this segment only; Figs. 12 and 13 represent the beginning and end of this period; third; interval u^1 during which the auxiliary brush is in contact with segments 2^a and 3^a ; beginning and end represented in Figs. 13 and 14. 120

Beginning now with the moment when the segment 1^a has just left the auxiliary brush (commutator moving with relation to the 125 brushes in direction of the arrow f), the action will be as follows: during period v^1 the action will be exactly as described in connection with a commutator with dead segments, Fig. 3; electromotive force E^1 will 130

simply transfer the armature current from the main to the auxiliary brush. At the beginning of the period w^1 the electromotive force E^1 reverses in direction and increases rapidly to such value as to completely reverse the current in the short-circuited coil o^1 and, preferably, make it to reach a value somewhat in excess of normal armature current, as shown at N^1 in Fig. 15, which represents the variation of current i_h collected from the segment 2^a during the time $v_1 + w_1 + u_1$. After reaching its maximum value, the electromotive force E^1 rapidly decreases and remains practically zero during the short period u^1 when the coil o^1 is short-circuited directly by the auxiliary brush. As the contact resistance of the latter is assumed to be high, and the current in the coil o^1 has already very nearly its final value, no sparking can result from this direct short-circuit of the coil.

Thus a sparkless commutation can be obtained even while it is impossible to introduce a reversing electromotive force in the circuit of a short-circuited coil at the precise moment of termination of the commutation process.

One of the most important advantages derived from the use of any satisfactory device for improving the commutation is economy effected by using fewer commutator segments and stronger armature, *i. e.*, with more ampere-conductors along the periphery. These conditions lead to designs with high self induction per coil, and the commutation is liable to be somewhat sluggish during that part of the commutation process when no external means of assisting it are used. The reversal of the current will then take place toward the end of the short-circuit; this will require considerable care in adjusting the electromotive force E^1 to its proper value and wave shape; also the distribution of current under the brush will be far from uniform, and a part of the main brush will be more or less useless for collection of the current. From another point of view; it is well known that as long as the current in the short-circuited coils follows "straight line" law of variation, it has no effect on the main field, action of the current flowing in one direction being counterbalanced by the action of the current flowing in the opposite direction; but if the commuted current either always exceeds the ideal "straight line" value, or is always below it, it begins to react on the main field in such a way that in case of under commutation the main field of a motor is strengthened, while in a generator it is weakened. This action is rather useful in a motor, because it makes the operation stable and prevents hunting, especially in motors built for adjustable speed duty; but it is in every respect detrimental in a generator. For these reasons, in many cases

it may be of advantage to accelerate the reversal of the current not only at the end, but also at the beginning or at any other part of the commutation process. This invention can be easily applied to such cases. If the special commutator of Fig. 3 is used, the reversing electromotive force can be introduced at the beginning of the commutation period by an arrangement shown in Fig. 16. It is similar to that of Fig. 3, but a second auxiliary brush D^3 , covering less than a dead segment, is added; it is connected to the main brush C^2 by a resistance r^3 , inductive or not, and by a coil n^3 in which a suitable alternating electromotive force is generated by means of an apparatus such as shown in Fig. 3. Connections and proportions of the other auxiliary brush D^2 are similar to those of the brush D of the Fig. 3. Line lead q^2 is attached to the main brush C^2 . The action of the brush D^3 is, briefly, as follows: during the interval of time when the main brush C^2 and the auxiliary brush D^3 are on the adjacent segments, as shown in Fig. 16, the electromotive force in the coil n^3 gives a sharp impulse in the direction of the reversal of the current in the short-circuited coil o^2 . When, immediately afterward, brushes C^2 and D^3 touch the same segment 2^b , the electromotive force in n^3 , acting now in the opposite direction, is used for transferring the current from the auxiliary to the main brush so as to gradually annul the current in the auxiliary brush, preparatory to its entering upon the dead segment 2^a .

In the case of commutators of usual construction, without dead segments, this invention can be applied in a similar way, except that the reversing electromotive force cannot be introduced in the circuit of a short-circuited coil at the precise moment of the beginning or the end of the commutation process, but it can be introduced at any other moment during this process, and as closely as desired to the beginning or the end. Figs. 17 and 18 show arrangement by means of which a reversing electromotive force acts twice upon a short-circuited coil while it is undergoing commutation. The brush consists of three parts, C^3 , C^4 , C^5 , which, for simplicity's sake, are represented as equidistant and at the same width—less than the width of a segment—although many other arrangements and proportions can be conceived, all based on the principle explained below, the only limitation being that the distance between any two consecutive brushes must be less than the width of a segment. External current is taken from the brush C^3 by the lead q^3 . Every two consecutive brushes are connected by a coil, such as n^5 and n^6 . Resistances and self inductions can be used in series with these coils, or with the brushes, if desired, although, in this case, it is pref-

erable to use a generator with poor regulation to avoid losses due to the main current flowing in resistances. Alternating electromotive forces of suitable phases, wave shapes and intensities, are induced in coils n^5 and n^6 . Action is as follows: while brushes occupy positions as in Fig. 17, *i. e.*, when two consecutive brushes are separated by an insulation between the segments, electromotive forces in coils n^5 and n^6 give an impulse in the direction of the reversal of the commuted current, the values of these electromotive forces being preferably considerably in excess of the sum of all injurious electromotive forces opposing the commutation in respective coils. When brushes are in a position such as in Fig. 18, *i. e.*, when coils n^5 and n^6 are shunted by commutator segments, the electromotive forces, acting in the opposite directions, help to transfer the current from one brush to the other. Electromotive forces are preferably arranged so as to have a large interval of zero value, during which the commutation is completed without external assistance, the commuted current having already reached nearly its final value. This also precludes the possibility of an electromotive force of wrong direction being applied to the coil because of an imperfect contact between the brush and the commutator.

In Fig. 19, H—G is the curve of the commuted current during a complete commutation period T of a coil; current passes from a value $+ia$ to the value $-ia$; parts of the curve marked H correspond to positions such as shown in Fig. 18; parts marked G to positions such as shown in Fig. 17. J shows the ideal "straight line" commutation curve. It can be seen thus, that a commutation closely similar to the "straight line" can be obtained, so that currents in the short-circuited coils will have little or no influence on the main field.

It is clear that instead of three brushes, any number could be used in the same way, giving correspondingly greater number of reversing impulses during commutation period. In difficult cases of commutation best results can be obtained by the use of arrangements similar to Fig. 3 or Fig. 16, but with main brush subdivided, as in Figs. 17 and 18.

In all preceding descriptions of various methods of applying this invention, it has been assumed that the alternating electromotive force was generated in an apparatus similar to the one shown in Fig. 3. It must be understood, however, that any kind of apparatus generating an alternating electromotive force of suitable frequency, wave shape and intensity can be used.

Investigation of the commutation process of a normally proportioned machine shows that the energy output of a generator producing the electromotive force used in the way described above, is exceedingly small

comparatively to the output of the machine itself. In many cases, therefore, it will be possible to do away entirely with a separate generator and produce the electromotive force E in the machine itself. This can be accomplished by introducing a variable resistance in a circuit acted upon by an electromotive force proportional to the current to be reversed, or by shunting, is made to flow. In both cases, a unidirectional pulsating current will be obtained, which can be put in inductive relation with a circuit where the alternating electromotive force E is to be generated. The variable resistance is preferably formed as a contact resistance, such as exists between a brush and a commutator, the variation of the resistance being obtained by variation of contact area according to a predetermined law, combined, if necessary, with variation of specific contact resistance of materials along the area of contact.

An arrangement of this kind is shown in Fig. 20. A⁴ is a commutator with dead segments similar to the one described with reference to Fig. 3. D⁴ are two brushes set approximately symmetrically with reference to the center line Po—Po midway between poles N and S; these brushes may consist of a homogeneous material all along the area of contact, or they may be composed of materials of different specific contact resistances, such as d¹ and d² in Fig. 20; part d¹ is made of a high contact resistance material, such as carbon; part d² is made of a low contact resistance material, such as copper or copper carbon combination; the total variation of resistance is thereby greatly increased. Current collecting brushes and auxiliary brushes, which would be set on the line Po—Po and could be of any variety described above, are, for the sake of clearness, omitted in Fig. 20.

It is clear that with the brushes D⁴ located as above, the electromotive force generated between these brushes depends only on the armature current, and will be practically proportional to it if the brushes D⁴ are set so as to embrace only non-saturated teeth. This electromotive force acts on the coil m⁴ through a resistance r⁴; the latter can be so adjusted as to give any desired value to the time constant of the circuit consisting of the coil m⁴, resistance r⁴, contact resistance of brushes D⁴ and impedance of the armature winding between the brushes D⁴. It will be found that in normally proportioned dynamo-electric machines the time constant of this circuit can be made very small without excessive loss; an excessive damping by the self induction can thus be avoided. Coil m⁴ acts inductively on a coil n⁴, in which an alternating electromotive force is thus generated. If several coil sides are located in the same slot, the electromotive force in n⁴

can be made to suit each individual coil in the slot by varying the peripheral width of dead segments. As a rule, current taken from this device will be too small to cause 5 sparking under brushes D'.

- A similar device can be used in connection with a commutator of the usual type, *i. e.* without dead segments. It is based on the following principle: it is well known that 10 except in the case of "straight line" commutation, the distribution of the current along the brush is not uniform, but can be imagined as a superposition of a uniformly distributed current, equal to the current delivered 15 by the brush to the brush stud, (called main current hereinafter) and of circulating currents flowing in the local circuits consisting of the short-circuited coils, contact resistances of the brush and the body 20 of the brush; at no load and with brushes set on magnetic neutral between the poles these circulating currents depend on the strength of field produced by the armature and on the self-induction of the short-circuited coils; 25 they are, therefore, proportional to the armature current; with the brushes shifted from magnetic neutral toward either pole, they depend also on the strength of the field produced by the poles.
- 30 Suppose now that the main brush is divided in two parts C⁶ and C⁷, Figs. 21 and 22, connected by a resistance r⁵ and a coil m⁵. Current collected from the commutator is conveyed to the brush stud by conductor 35 q⁵ attached to the brush C⁶. Figs. 21 and 22 represent two extreme positions of the brushes C⁶ and C⁷ with reference to the commutator, supposed to be rotating in direction of the arrow f; in Fig. 21 brushes 40 cover two adjacent segments 2° and 3°. It is clear that in Fig. 21 the part of the main and the circulating currents corresponding to the brush C⁷ flow toward or away from the conductor Q⁵ and the brush C⁶ respectively through the coil m⁵ and resistance r⁵; but in the position shown in Fig. 22 this path is shunted by the double contact resistance of brushes C⁶ and C⁷ with the segment 3°. Current in the coil m⁵ will, therefore, 45 pulsate periodically, and can be utilized for generating by induction an alternating electromotive force in a coil n⁷ which connects the brush C⁷ with an auxiliary brush D⁵, thus assisting the commutation in the way 50 described in connection with Figs. 11 to 14. It is clear that a brush for assisting the commutation at the beginning of commutation process could also be used, alone or in connection with D⁵.
- 55 The efficiency of this device, as well as of that shown in Fig. 20 can be materially improved by connecting a condenser c (Figs. 21 and 22) across the terminals of the coil m⁵; with suitable wave shape of the current 60 in the coil m⁵ an exchange of energy between

the condenser and the self-induction of the coil will be set up, through medium of a current circulating in the circuit of the coil m⁵ and the condenser, but not passing through the resistance r⁵; pulsating flux set up by the 70 coil m⁵ will be thus intensified without any loss in resistance.

By varying the relative size of brushes C⁶ and C⁷ any desired fraction of the main current can be made to flow in the coil m⁵. 75 The law of variation of the current in m⁵ can be regulated by giving an appropriate shape to the areas of contact of brushes C⁶ and C⁷ with the segment 3°.

This device has the advantage of being 80 not sensitive to the brush position, because a wrong position of brush intensifies the circulating currents and, therefore, the reversing electromotive force. When electromotive forces of different phases or different 85 wave shapes are desired, the main brush can be divided in more than two parts, every two consecutive parts being connected by coils such as m⁵.

A simple calculation shows that the current density under brush C⁶ and segment 3° 90 has always a finite value as long as the specific contact resistance of this brush is different from zero; excessive current density and sparking under the brush C⁶ can, therefore, 95 be always eliminated.

Figs. 23 and 24 show a method of applying my invention especially suitable for machines in which the strength of combined main pole and armature reaction field is 100 approximately proportional to the armature current, as in series wound traction motors. C⁸ is main current collecting brush, of any desired width; D⁶ and D⁷ are auxiliary brushes, of the width less than a segment, 105 and made of a material of equal or higher contact resistance than the main brush. These auxiliary brushes are connected to the main brush respectively by coils n⁸ and m⁶ which are in inductive relation to each other. 110 For the direction of rotation indicated by the arrow f an armature coil begins the commutation process under the brush D⁷ and completes it under the brush D⁶. Current collected from the brushes is carried to the 115 brush stud by conductor q⁶ attached to the main brush. The action of this combination is as follows:

During the time when the commutator moves from the position of Fig. 23 to that 120 of Fig. 24 the armature coil o⁶ is short-circuited by the coil m⁶; current in the latter increases from a minimum value to a certain maximum value at the end of this period; after that coil m⁶ is shunted by the segment 125 3° and the current decreases to the minimum value, current collected from the connector z⁶ passing from the auxiliary brush to the main brush without external assistance, because the specific resistance of the auxiliary 130

brush is at least as high as that of the main brush. A unidirectional pulsating current will flow in the coil m^6 and if the coils m^6 and n^8 are so proportioned that the action of m^6 is predominant, an electromotive force will be generated in n^8 which can be used for completing the commutation of another armature coil O_7 in the same way as has been explained in connection with Figs. 11 to 14.

Within its proper sphere of application this arrangement is an electrical equivalent of improving the commutation by shifting the brushes, inasmuch as the reversing electromotive force in the coil n^8 depends (indirectly) on the strength of the field ahead of the main brush, same as in motors with brushes shifted against rotation; yet, the line of symmetry of the main brush can remain on the magnetic neutral, and the advantage of reversibility is not lost; it is only necessary to bring the terminals of the coils m^6 and n^8 —either directly, or by means of transformers—to the reversing drum of the controller, so as to reconnect them when the direction of rotation of the motor is reversed. Another advantage is the possibility, or even the advisability of using a large polar arc, which leads to an economical design.

Of course, for a correct application of this arrangement, it is necessary that the electromotive force induced in the armature coil O^6 while it is short-circuited through the coil m^6 has such direction as to assist the reversal of the current in this coil; that is, in case of a motor, the field of the main poles must be stronger than the armature field in the region where the armature coil O^6 is located during this interval.

It is obvious that various changes may be made in the details of construction and arrangement of parts, within the scope of the claims, without departing from the spirit of this invention. It is, therefore, to be understood that this invention is not to be limited to the specific details and arrangements shown and described.

Having thus described the invention, what is claimed is:

1. In a dynamo-electric machine, an armature having armature coils, a commutator connected to said armature coils, brushes bearing on said commutator, and means for applying an alternating electromotive force between said brushes, said parts being constructed and arranged that when the applied electromotive force acts in a direction suitable for reversal of the current in the short-circuited coil, the circuit containing the electromotive force closes through said coil, while when the electromotive force acts in a direction opposing the reversal of the current, the circuit containing the electro-

motive force is shunted by a commutator segment, for the purpose set forth. 65

2. In a dynamo-electric machine, an armature having armature coils, a commutator connected to said armature coils, sets of brushes bearing on said commutator, the adjacent brushes of a set being spaced peripherally less than the width of a commutator segment, and means for applying an alternating electromotive force between the brushes of a set, the electromotive force acting in one direction while the brushes of a set between which the electromotive force is applied are separated by the insulation between adjacent segments, and acting in the opposite direction while said brushes bear on 80 the same segment.

3. In a dynamo-electric machine, an armature having armature coils, a commutator connected to said armature coils, sets of brushes bearing on said commutator, the adjacent brushes of a set being spaced peripherally less than the width of a commutator segment, means for applying an alternating electromotive force between the brushes of a set, the electromotive force acting in one direction while the brushes of a set between which said electromotive force is applied are separated by the insulation between adjacent segments, and acting in the opposite direction while said brushes bear on 95 the same segment, and a resistance and a reactance in circuit with said brushes and said means.

4. In a dynamo-electric machine, an armature having armature coils, a commutator connected to said armature coils, sets of brushes bearing on said commutator, a conducting connection between certain of said brushes, and a conducting connection between certain of said brushes and in inductive relation with said first conducting connection, and resistances and reactances in one of said conducting connections, said first conducting connections being arranged so as to be intermittently shunted by the commutator segments, for the purpose set forth. 100 105 110

5. In a dynamo-electric machine, an armature having armature coils, a commutator connected to said armature coils, sets of brushes bearing on said commutator, a conducting connection between certain of said brushes, and a conducting connection between certain of said brushes and in inductive relation with said first conducting connection, and resistances and reactances in 115 120 125 series with and capacities in shunt with one of said conducting connections, said first conducting connections being arranged so as to be intermittently shunted by the commutator segments, for the purpose set forth.

In testimony whereof I affix my signature this 17th day of April, 1916.

JAROSLAW K. KOSTKO.
